C. E. CHAPMAN

PRIMING DEVICE FOR INTERNAL COMBUSTION ENGINES

Filed July 8, 1922

UNITED STATES PATENT OFFICE.

CHARLES E. CHAPMAN, OF FORT EDWARD, NEW YORK, ASSIGNOR OF ONE-HALF TO
JOSEPH GOODFELLOW, OF FORT EDWARD, NEW YORK.

PRIMING DEVICE FOR INTERNAL-COMBUSTION ENGINES.

Application filed July 8, 1922. Serial No. 573,641.

To all whom it may concern:

Be it known that I, CHARLES E. CHAPMAN, citizen of the United States, residing at Fort Edward, in the county of Washington and State of New York, have invented 5 certain new and useful Improvements in Priming Devices for Internal-Combustion Engines, of which the following is a specification.

10 This invention relates to an improved priming device for internal combustion engines and seeks, as one of its principal objects, to provide a device of this character whereby an engine may, in cold weather, be 15 started quickly and easily.

The invention has as a further object to provide a device which will operate to deliver a rich fuel mixture into the engine cylinders so that ignition may readily take place 20 and wherein the injection of liquid fuel into the cylinders will be avoided.

Another object of the invention is to provide a device embodying a throttle valve controlling the flow of fuel mixture to the 25 engine cylinders and also embodying a fuel valve controlling feed of the liquid fuel and wherein means will be provided for operating said valves simultaneously so that when the throttle valve is opened, flow of liquid 30 fuel will be permitted and vice versa.

A still further object of the invention is to provide a device embodying a combined air intake and mixing tube, wherein said tube will be closed by a mixing screen, and 35 wherein the liquid fuel will, when the valves of the device are open, be permitted to drip onto said screen to be broken up thereby and mixed with the inrushing air to form a rich fuel mixture.

40 The invention has as a further object to provide a device wherein the liquid fuel will be fed thereto by gravity so that the troubles experienced in extremely cold weather in attempting to lift the fuel by engine suction 45 will be overcome.

And the invention has as a still further object to provide a device which may be readily installed and which may be employed in connection with motor vehicle engines of 50 conventional make.

Other and incidental objects will appear hereinafter.

In the drawings:

Figure 1 is a fragmentary side elevation showing my improved device in connection with the engine of a motor vehicle, parts being broken away and shown in section. 55

Figure 2 is an enlarged detail view of the device, partly in elevation and partly in section, and 60

Figure 3 is a transverse sectional view on the line 3—3 of Figure 2, looking in the direction of the arrows.

Referring now more particularly to the drawings, I have, for convenience, shown 65 my improved priming device in connection with the engine of a conventional motor vehicle. The engine is indicated at 10 and the intake manifold thereof at 11. Connected to said manifold is the usual carburetor 12 having the customary choke valve 13 to which is connected a priming rod 14 operable from the driver's seat of the vehicle for manipulating the valve. The vehicle dash is indicated at 15 and the engine 70 radiator at 16. Extending between the dash and radiator is the customary brace rod 17. 75

Coming now more particularly to the subject of the present invention, I employ an L-shaped body bar 18 at the lower end of which is arranged a vertically disposed throttle valve casing 19 upon which is mounted a throttle valve 20. Threaded into the valve casing at its upper end is a combined air inlet and mixing tube 21 providing a mixing chamber 22 and removably fitting in the upper end of said tube is a sleeve 23 having a flange 24 overhanging the upper end edge of the tube. This sleeve 80

is removably secured in position by a set screw 25 and mounted upon the sleeve is a combined atomizing and closure screen 26. The screen is preferably frusto-conical in shape and is arranged in inverted position to depend within the sleeve, the screen being appropriately secured at its larger end to the wall of the sleeve at the upper end thereof. As will be apparent, the sleeve may, by releasing the set screw 25, be readily removed so that the screen may be easily 95 100

2
cleaned at any time and, in this connection, attention is directed to the fact that the screen lies within the lines of the sleeve so that when the sleeve is so removed, the 5 sleeve will house and protect the screen. Threaded into the valve casing 19 at its lower end is an elbow 27 having a pipe 28 extending therefrom which pipe, as shown in Figure 1, leads into the intake manifold 10 11 of the engine, and interposed in said pipe is a union 29 so that the pipe may be readily connected to the manifold.

Mounted upon the body bar 18 at its upper end is a horizontally disposed fuel valve 15 casing 30 mounting a fuel valve 31 projecting at the forward end of the casing and provided with an upturned arm 32. Mounted upon the vehicle dash is an appropriate liquid fuel tank 33 arranged above the level 20 of the fuel valve and extending from said tank is a supply pipe 34 connected to the rear end of the valve casing 30, a suitable shut-off valve 35 being preferably interposed in said pipe. Mounted upon the valve 25 casing 30 at its lower side is a depending drip nozzle 36 disposed axially of the air inlet and mixing tube 21. At its upper end this nozzle is provided with an annular head threaded through the wall of the valve 30 chamber of the valve casing while, as brought out in Figure 3, the nozzle is preferably square in cross section throughout its length below said head. Formed in the side faces of the nozzle are 35 drip slots 37 which extend longitudinally of the nozzle from end to end thereof to open through the head at the upper end of the nozzle, these slots being relatively narrow so as to permit a restricted flow of fuel 40 therethrough. Upstanding from the valve casing 30 is a lug 38 and bolted or otherwise secured to said lug is a hanger strap 39 appropriately secured at its upper end to the brace rod 17 rigidly connecting the device with said rod.

Extending rearwardly from the body bar 18 is a horizontally directed arm 40 and pivoted at a point between its ends upon said arm is a lever 41. Extending between 50 the upper end of the lever and the arm 32 of the fuel valve 31 is a link 42 and extending between the lower end portion of the lever and the throttle valve 20 is a link 43. Formed on or otherwise secured to the elbow 27 is an eye 44 and extending between said eye and the lower end portion of the lever 41 is a spring 45 acting upon the lever for normally holding the valves 20 and 31 closed. However, in order to avoid failure 55 in the closing of the valve 31, due to looseness in the pivotal connections between the lever 41 and said valve, I provide an auxiliary spring 46 connected at one end to the lug 38 and at its opposite end to the arm

32 of the valve, this spring acting to close the valve 31 individually so that the valve will, under normal circumstances, be tightly held in engagement with its seat so as to prevent leakage of fuel past the valve. Pivotally connected to the lower end of the 70 lever 41 is a link 47 which extends rearwardly from said lever and, as shown in Figure 1, is suitably attached to the priming rod 14.

As will now be readily understood in view 75 of the preceding description, when the priming rod 14 is pulled rearwardly for choking the air inlet of the carburetor 12, the rear end of the lever 41 will be rocked rearwardly so that, as shown in dotted lines in 80 Figure 2 of the drawings, the valve 20 will be pulled rearwardly to open position while the valve 31 will be shifted forwardly to open position. Accordingly, liquid fuel will then be permitted to gravitate from the 85 tank 33 into the valve casing 30 to drip through the slots 37 from the nozzle 36 onto the atomizing screen 26. Coincident with the actuation of the priming rod 14, the 90 engine starter is, of course, set in operation so that engine suction in the pipe 28 will cause the liquid fuel to be drawn through 95 said screen along with a supply of air. Thus, the liquid fuel, in being drawn through the screen, will be broken up not only by the screen but also by the inrushing air passing through the screen so that the liquid fuel will accordingly be thoroughly atomized and mixed with the air in 100 the mixing chamber 22. As will be perceived, a rich fuel mixture will thus be formed, which mixture will be drawn from the mixing chamber through the throttle valve to the engine cylinders where, due to the richness of the mixture, ignition will 105 readily take place. The device will thus function to insure quick starting of the engine even during extremely cold weather and, in this connection, it is to be noted 110 that by arranging the supply tank 33 so that the liquid fuel will gravitate to the drip nozzle, the necessity for lifting the fuel by engine suction is eliminated and consequent failure under adverse weather conditions overcome. Furthermore, it is to be noted that when the priming device is functioning and the throttle valve 20 is open so that air may freely flow through the mixing chamber into the intake manifold of the engine, the engine suction to the carburetor of the engine will be reduced, with the result that air taken in through the mixing screen at the upper end of the mixing chamber will attain a proportionately higher velocity. Accordingly, air rushing into the 115 mixing chamber at this point will serve to effectively break up the liquid fuel falling upon the mixing screen.

Having thus described the invention, what is claimed as new is:

1. A priming device for internal combustion engines including a body bar, a fuel valve carried by said bar and provided with a depending drip nozzle, a throttle valve upon the bar provided with an upstanding mixing tube having its upper end disposed to receive fuel dripping from said nozzle, an arm extending from the bar, a lever pivoted upon said arm, and links extending between the lever and said valves, the lever being operable for simultaneously opening or closing the valves. 75
15. 2. In a priming device for internal combustion engines, a fuel nozzle discharging fuel independent of engine suction, a fuel valve controlling flow of fuel through the nozzle, a mixing chamber open to the atmosphere and disposed to receive fuel issuing from said nozzle, a throttle valve associated with said chamber, and means for operating said valves. 80
20. 3. In a priming device for internal combustion engines, a fuel nozzle discharging fuel independent of engine suction, a fuel valve controlling flow of fuel through the nozzle, a mixing chamber terminating at one end beneath the nozzle to receive fuel issuing from said nozzle and having said end thereof in unobstructed communication with the atmosphere, a throttle valve associated with said chamber, and means for operating said valves. 85
25. 4. In a priming device for internal combustion engines, a fuel nozzle flowing fuel under the pressure head of a fuel supply, a fuel valve normally cutting off flow of fuel to the nozzle, a mixing chamber open to the atmosphere and disposed to receive fuel issuing from said nozzle, a throttle valve associated with said chamber, and means for operating said valves. 90
30. 5. In a priming device for internal combustion engines, a fuel nozzle discharging fuel independent of engine suction and provided with a slot therein whereby fuel may drip from the nozzle through said slot, a fuel valve controlling flow of fuel through the nozzle, a mixing chamber open to the atmosphere and disposed to receive fuel dripping from said nozzle, a throttle valve associated with said chamber, and means for operating said valves. 95
35. 6. In a priming device for internal combustion engines, a fuel nozzle discharging fuel independent of engine suction, a fuel valve controlling flow of fuel through the nozzle, a mixing chamber open to the atmosphere and disposed to receive fuel issuing from said nozzle, a mixing screen in said chamber, a throttle valve associated with the chamber, and means for operating said valves. 100
40. 7. In a priming device for internal combustion engines, a fuel nozzle discharging fuel independent of engine suction, a fuel valve controlling flow of fuel through the nozzle, a mixing chamber disposed to receive fuel issuing from said nozzle, a fuel valve controlling flow of fuel through the nozzle, a throttle valve associated with said chamber, a pivoted lever, and means connecting the valves with said lever at opposite sides of the pivotal center thereof whereby the lever may be operated for opening or closing said valves 105
45. 8. In a priming device for internal combustion engines, a fuel nozzle discharging fuel independent of engine suction, a fuel valve controlling flow of fuel through the nozzle, a mixing chamber having one end thereof in unobstructed communication with the atmosphere and disposed below the nozzle to receive the fuel flowing therefrom, and a mixing screen mounted in said end of the chamber whereby fuel flowing from the nozzle 110
50. will strike the screen at the mouth of said chamber. 115
55. 9. In a priming device for internal combustion engines, a fuel nozzle flowing fuel under the pressure head of a fuel supply, a mixing chamber having one end thereof in unobstructed communication with the atmosphere and disposed to receive fuel flowing from the nozzle, a fuel valve controlling flow of fuel through the nozzle, a mixing chamber open to the atmosphere and disposed to receive fuel issuing from said nozzle, a fuel valve normally cutting off flow of fuel to the nozzle, and means for opening or closing the fuel and throttle valves simultaneously operatively connected with said choke valve. 120
60. 10. In a priming device for internal combustion engines, a fuel nozzle discharging fuel independent of engine suction, a fuel valve controlling flow of fuel through the nozzle, a mixing chamber open to the atmosphere and disposed to receive fuel issuing from said nozzle, a mixing screen disposed in said end of the chamber, and means detachably mounted upon the chamber supporting the screen. 125
65. 11. In a priming device for internal combustion engines, a fuel nozzle flowing fuel under the pressure head of a fuel supply, a mixing chamber having one end thereof in unobstructed communication with the atmosphere and disposed to receive fuel flowing from the nozzle, a fuel valve controlling flow of fuel through the nozzle, a mixing chamber disposed to receive fuel issuing from said nozzle, a fuel valve controlling flow of fuel through the nozzle, a throttle valve associated with said chamber, a pivoted lever, and means connecting the valves with said lever at opposite sides of the pivotal center thereof whereby the lever may be operated for opening or closing said valves. 130

13. The combination with an internal combustion engine having an intake manifold and a carburetor connected with said manifold, of a primer including a mixing chamber open to the atmosphere and connected to the manifold between the carburetor and engine, a fuel nozzle discharging fuel into said chamber independent of engine suction, a fuel valve controlling flow of fuel through

the nozzle, and a throttle valve associated with said mixing chamber and controlling the intake of air through the mixing chamber into the manifold reducing engine suction to the carburetor when said throttle valve is open.

In testimony whereof I affix my signature.

15

CHARLES E. CHAPMAN. [L.S.]
